(57) **CLAIM**

The ornamental design for a dance pole base, as shown and described.

DESCRIPTION

FIG. 1 is perspective view of a dance pole base according to my new design;

FIG. 2 is a top view of the base of FIG. 1; and,

FIG. 3 is a side view of the base of FIG. 1.

The broken lines in FIG. 2 illustrate an unknown depth portion of the dance pole base and form no part of the claimed design.
